SHIFT-SPEED CONTROL FOR OUTBOARD MOTORS

Elmer C. Kiekhaefer, Cedarburg, Wis.

Application February 14, 1952, Serial No. 271,507

6 Claims. (Cl. 115—18)

1

This invention relates to outboard motors having selective drive transmissions and particularly to the coordinated speed and shift control of the motor.

The invention provides an improved coordinated control of the selective drive or shift mechanism and the speed adjustment which latter is more readily adjustable in relation to the operation of the shift mechanism.

An object of the invention is to provide a more dependable and rugged coordinated control.

Another object is to allow for the more ready adjustment of the interengaging abutments of the speed control and shift mechanism.

Another object is to dispose the adjustment forwardly of the engine for easy access.

Another object is to more firmly secure the shift control lever in the forward and reverse positions.

Another object is to provide a smoother operating coordinated shift and speed control by means of the tiller handle.

Another object is to allow the tiller to be shifted out of the way of the operator in the boat without effecting the shift speed control means.

These and other objects and advantages will be more fully set forth in the following description of a preferred embodiment of the invention, as illustrated in the accompanying drawings.

In the drawings:

Figure 1 is a front elevation of the upper end of an outboard motor with parts removed to show the front of the engine. The tiller is shown in a raised position and the shift control in a neutral position with the speed control adjusted to the allowed maximum "neutral" speed.

Fig. 2 is a side elevation of the outboard motor showing the engine in part and with portions of the drive shaft housing and supporting bracket assembly broken away and sectioned to show the construction thereof. The tilt lock device is shown engaged as in the reverse position of the shift mechanism;

Fig. 3 is a view showing the tilt lock device disengaged as in the forward or neutral position of the shift mechanism;

Fig. 4 is an enlarged sectional view of the lower end of the drive shaft housing and the propeller drive unit showing the shift control mechanism in the forward drive position;

Fig. 5 is a side elevation of the engine of the motor with the flywheel and the magneto partially broken away to show the construction thereof;

Fig. 6 is a front elevation of the engine of the motor with the shift control in the reverse position and the speed control adjusted to the allowed maximum speed;

5

Fig. 7 is a top plan view of the speed control mechanism with parts of the tiller broken away and sectioned and showing the control lever of the shift control mechanism in the forward position with neutral and reverse positions indicated by dotted lines;

Fig. 8 is a top plan view of parts of the carburetor control and adjustment; and

Fig. 9 is a view showing the speed control at low speed and the cam adjustment of the carburetor closing the carburetor for lower speeds of operation.

15

The engine 1 of the outboard motor shown in the drawings includes the cylinder block 2 and the crankcase 3 which are joined by the bolts 4. The crankshaft 5 supported by crankcase 3 extends upwardly and carries the hub 6 of the flywheel 7 above the magneto 8 which provides for the ignition of the engine. The magneto stator plate 9, which carries the stators 10, is mounted on the upper end of crankcase 3 for rotational adjustment relative thereto on the axis of crankshaft 5 and supports the breaker mechanism 11 for a corresponding rotational adjustment therewith. The rotor 12 is carried by crankshaft 5 to provide a rotating magnetic field which induces an electric current in the windings of stators 10.

25

The hub 6 mounted on crankshaft 5 above rotor 12 is provided with a cam profile which operates breaker mechanism 11 in timed relation to the rotation of the rotor 12 and crankshaft 5. Rotation of plate 9 effects an advance or retarding of the ignition as required for the control of the engine. The flange 13 of flywheel 7 extends around the magneto and plate 9.

35

The carburetor 14 is carried by crankcase 3 forwardly of engine 1 and includes the mixing passage 15 which is open at one end to receive air. The opposite end communicates with the crankcase induction system of the engine, not shown, for delivery of a fuel and air mixture thereto. The shutter 16, mounted within passage 15 on the vertical shaft 17 extending through passage 15, is disposed to open and close passage 15 with rotation of shaft 17 for the control of the fuel induction of the engine.

40

Engine 1 is supported on the upper open end of the hollow housing 18, which encloses the drive shaft 19 connected to the lower end of crankshaft 5 projecting into the housing. The shoe member 20 closes the lower end of housing 18, which extends rearwardly of the motor and includes a discharge outlet for the underwater discharge of the exhaust which is received from engine 1 at the upper end of housing 18.

55

The outboard motor is supported by the bracket assembly 21 which includes the clamp bracket

22 provided with turn screws 23 by which bracket 22 is adapted to be firmly secured to a transom of a boat, not shown. The swivel bracket 24 is carried by bracket 22 on the transverse horizontal tilt bolt 25 and is fitted with the hollow vertical pivot pin 26. Lugs 27 and 28, formed integrally with housing 18, support the housing on the upper and lower ends of pin 26 and provide for rotational movement of housing 18 including engine 1 and the lower unit 29 for steering of the boat, not shown, by means of tiller 30.

The lower unit 29 includes the propeller 31, which is carried by the gear case 32 secured with member 20 by the bolts 33 and 34 to the lower end of housing 18. The streamlined gear case housing 32 is provided with a chamber 35 for the gear transmission system of the motor. The upper and lower bearings 36 and 37, respectively, in housing 32 support the lower portion of shaft 19. The lower end of shaft 19 extends into chamber 35 and carries the beveled drive gear 38.

The propeller shaft 39 is supported within chamber 35 at the forward end by bearing 40 and also by the bearing 41 and bushing 42 disposed within chamber 35 rearwardly of gear 38. The beveled forward drive gear 43 is freely supported by shaft 39 and in mesh with gear 38. The beveled rear drive gear 44 disposed on shaft 39 and in mesh with gear 38 for rotation oppositely of gear 43 is supported independently of shaft 39 by bearing 45. The clutch teeth 46 are formed in adjacent, oppositely facing parts of gears 43 and 44 and are selectively engageable by the cross bar 47 movable axially of shaft 39 in the slot 48 formed in the shaft.

The spring 49 within the central axial bore 50 in shaft 39 is disposed to urge bar 47 forwardly in slot 48 and into engagement with teeth 46 of gear 43 to effect rotation of shaft 39 and propeller 31 in the direction of rotation for forward propulsion.

The pin carried by shaft 39 in bore 50 is disposed forwardly of bar 47 and projects from the forward open end of bore 50. The rotatable control shaft 52 is supported vertically in the forward portion of gear case 32 and is provided at its lower end with the eccentric 53 which is disposed forwardly of pin 51 and carries the roller bearing unit 54 for engagement with pin 51. The reverse gear mechanism described is similar to that disclosed and claimed in the present inventor's application filed December 23, 1950, Serial No. 202,479 for Reverse Gear and Outboard Motor Underwater Unit.

The rotation of control shaft 52 is effected by the shift lever 55 mounted on the upper end of the control rod 56 connected to shaft 52. Rotation of shaft 52 to a position, as shown in Fig. 4, moves eccentric 53 and roller 54 to a position allowing spring 49 to move bar 47 into engagement with clutch teeth 46 of gear 43. Rotation of shaft 52 by means of lever 55 moves eccentric 53 and roller 54 against the projecting end of pin 51 and moves the pin axially within bore 50 to engage bar 47 and move the latter against the action of spring 49 to a position intermediate gears 43 and 44. In the intermediate "neutral" position of bar 47, the gears 43 and 44 are rotated without engagement with bar 47 and allow engine 1 to operate without effecting the rotation of shaft 39 and propeller 31. Further rotation of shaft 52 moves eccentric 53 and roller 54 and pin 51 and bar 47 into engagement with clutch teeth 46 of gear 44 to effect rotation of shaft 39

and propeller 31 in a reverse direction with a consequent rearward propulsion of the boat.

According to the invention of the present inventor, as described and claimed in his application Serial No. 83,250 and filed March 24, 1949 for Engine Mounting and Control System, the control rod 56 extends through pivot pin 26 for rotation on the steering axis of the motor.

The cam 57 is secured on rod 55 so as to be turnable therewith and supports the cam member 58 mounted thereabove on rod 56. The axial slot 59 in the back side of cam member 58 fits the guide 60 projecting from housing 18 whereby member 58 is fixed rotationally and the rotation of cam 57 with rod 55 effects vertical (axial) movement thereof on rod 56.

The tilt adjustment bolt 61 selectively disposed in one of the series of holes 62 in bracket 22 is engaged by swivel bracket 24 in the forward direction of motor operation to secure the motor in the desired position of adjustment on bolt 25 while allowing the motor to tilt upwardly and rearwardly on bolt 25 for passing over submerged objects or lifting the motor from the water.

The hook 63 mounted on the transverse bearing 64 is carried by bracket 24 to engage bolt 61 and serves to secure the motor against tilting on bolt 25. The spring 65 connected between hook 63 and bracket 24 normally supports hook 63 in the raised position, as shown in Fig. 3. The lower arm 66 of hook 63 extends above cam member 58 so that rotation of rod 56 and cam 57 lifts cam member 58 to move hook 63 against the biasing of spring 65 and into engagement with bolt 61. Cam 57 and member 58 are rotationally adjusted to provide for actuation of hook 63 upon rotation of rod 56 to the reverse position of the rod and thus serves to secure automatically the motor against tilting on bolt 25 while in operation in reverse.

The tiller 30 for turning the outboard motor on the axis of pin 26 for steering includes the tube 67 supported within a projecting portion of the casting 68. The grip-handle 69 is rotatably carried at the forward end of tube 67 and secured to the shaft 70 which latter is rotatably supported within tube 67.

The tiller bracket 71 secured to housing 18 extends forwardly of engine 1 and supports the trunnion 72 having an axial center bore 73 which extends horizontally and transversely of the motor. A cylindrical portion of trunnion 72 is dimensioned to fit within the bore 74 of bracket 71 and is threaded at one end to receive the nut 75. Nut 75 secures the bracket 71 between the abutment 76 of trunnion 72 and the nut to secure the trunnion in bore 74 of bracket 71.

The large annular flange 77 of trunnion 72 fits within the open end of bore 78 of casting 68 and supports the tiller for rotation thereon. The washer 79 is secured by screws 80 to the end face of casting 68 and fits between the friction washer 81 on the outside of bracket 71 and flange of trunnion 72 to secure the casting thereon.

The stop member 82 extending from bracket 71 beneath casting 68 is disposed to be engaged by the projecting finger 83 formed integrally with the casting and limits rotation of tiller 30 on trunnion 72 in one direction to support the tiller and handle 69 forwardly of the motor.

The shaft 84 is supported for rotation in the center bore of trunnion 72 and extends transversely across the front of the motor over rod 56 and adjacent thereto. The beveled gears 85 and 86 are mounted on the adjacent ends of shafts

5

84 and 70, respectively, within casting 68 and provide for the rotational connection of the shafts while allowing rotational adjustment of the tiller on flange 76 which is concentric with the axis of shaft 84.

The end of shaft 84 oppositely of that carrying gear 85 is supported by the bracket 87 and carries the crank 88 on the outside of the bracket. The shaft hanger 89 is secured to the side of crank-case 3 and supports the vertical shaft 90. The crank 91 secured to the lower end of shaft 90 is connected to crank 88 by the link 92. The gear quadrant 93 bolted to the underside of magneto plate 9 meshes with gear sector 94 secured to the upper end of shaft 90 whereby the rotational adjustment of handle 69 effects a corresponding adjustment of magneto plate 9 through the mechanical connection of gears 85 and 86 and link 92.

The cam plate 95, carried by magneto stator plate 9, is disposed to engage the pin 96 supported by crank 97, which latter is mounted on the upper end of carburetor shaft 17. The plate 95 is supported by the bolt 98 within slot 99 of plate 95 from the arm 100 which depends from magneto stator plate 9. The lower end of arm 101 spaced from arm 100 pivotally secures plate 95 and allows for adjustment of the plate within slot 99 which determines the degree of engagement and disengagement with pin 96. The movement of pin 96 turns shaft 17 and shutter 16 in one direction in relation to the rotational adjustment of magneto plate 9.

According to the invention, the collar 102, secured on shaft 84 by the set screw 103, is disposed to be axially engaged by the pin 104 which projects upwardly from the member 105 to limit shifting of lever 55 and to engage pin 104 by rotation to limit the speed adjustment of handle 69. Lever 55 is carried by member 105 which is in the form of a sector and is fixed on the upper end of rod 56.

In the position of lever 55 which turns control rod 56 to effect the shifting of bar 47 to the neutral position described above, pin 104 is disposed in advance of the abutment face 106 of collar 102 to limit rotation of the collar and shaft 84 and determines the maximum "neutral" speed of the engine as effected by the turning of handle 69. A movement of lever 55, to rotate rod 56 and move bar 47 into driving engagement with gear 43, moves pin 104 adjacent to shaft 84 and spaced from the end of collar 102 with sufficient clearance to allow the full rotation of shaft 84 in either direction.

Rotation of handle 69 in one direction effects, as described, a corresponding rotation of shafts 84 and 90 and of magneto stator plate 9 to a retarded position of adjustment of the ignition timing. The rotational adjustment of magneto plate 9 moves cam plate 95 into engagement with pin 96 to turn shaft 17 and shutter 16, closing mixing passage 15 whereby the correlated control of carburetor 14 and the magneto is effected, as determined by the profile of cam plate 95.

Rotation of handle 69 in the opposite direction, which effects a corresponding advancement of magneto plate 9 and moves cam plate 95 therewith, allows the spring 107 to turn shaft 17 and effect reopening of passage 15 for intermediate and high speed operation of engine 1. At all speeds above the maximum "neutral" speed, the position of collar 102 on shaft 84 and adjacent to pin 104 limits movement of lever 55 preventing shifting of bar 47 out of engagement with drive gear 43. Rotation of shaft 84 and collar 102 by 70

6

adjustment of handle 69 to a reduced speed, as a prerequisite for shifting of lever 55, thus prevents shifting of bar 47 at high speeds with consequent damage to the transmission system and the motor. In the "neutral" position of pin 104 as shown in Figure 1, a relatively low maximum "neutral" speed is established by the pin which is disposed at such times in the path of abutment 106 of collar 102. Within the "neutral" speed range the adjustment of lever 55 for shifting of bar 47 into engagement with the rear drive gear 44 is allowed.

In the position of lever 55 providing engagement of bar 47 and gear 44 for reverse drive, pin 104 is aligned with the slot 108 in collar 102 which allows rotation of shaft 84 and collar 102 and the adjustment of the motor to a maximum determined by the depth of slot 108. In the maximum position of speed adjustment as effected by rotation of handle 69, pin 104 is secured in slot 108 of collar 102 against movement which prevents shifting of bar 47 by movement of lever 55 except with a reduction of engine speed as effected by rotation of handle 69 to the predetermined maximum "neutral" speed determined by abutment 106 of the collar.

The forward, neutral and reverse positions of lever 55 and rod 56, are generally secured by the spring 109 secured at one end by bracket 71 and engaging sector 105. The relative adjustment of the shift speed control effected by collar 102 is provided for by loosening set screw 103 and adjusting collar 102 axially or rotationally on shaft 84.

35 The axial adjustment of collar 102 allows the parts of the collar which are engaged by movement of pin 104 to be positioned accurately respecting rod 56 to minimize the "free play" of lever 55 and possible shifting of bar 47.

40 The rotational adjustment of collar 102 on shaft 84 allows the parts of the bushing which are engaged by movement of the collar, as with the control of the engine, to be positioned whereby the maximum "neutral" speed and maximum speed in reverse may be set as found to be most desirable.

45 In the securement of lever 55 in the forward and reverse positions, shifting of lever 55 is precluded by collar 102 on shaft 84 which latter is supported by brackets 71 and 87 and secured axially by the crank 88 and gear 85.

50 In attempts to shift at speeds in excess of that allowed by collar 102, pin 104 is forced against the end of the collar or axially thereof. By reason of the leverage afforded by control lever 55, the abutment means provided to preclude shifting before reducing speed must be rugged, able to withstand considerable abuse. The securement of lever 55 by collar 102 is provided so that such forces are received and supported by shaft 84 axially. The construction of the shift control is thus made extremely rugged notwithstanding its light weight and is easily accessible at the front of the motor for the full adjustment thereof as described.

55 Various embodiments of the invention may be employed within the scope of the following claims:

I claim:

1. In an outboard motor unit pivotally supported for steering movement on a vertical axis, an engine, a magneto at the upper end of the engine and having a stator plate rotatably adjustable to control the speed of the engine, a vertical shaft at one side of the engine and connected at the upper end to said plate to adjust the latter,

a lower propeller unit including transmission means selectively operable to effect a driving connection with said engine for propulsion in forward and reverse directions, a bracket carried by the motor unit and a transverse shaft supported by said bracket forwardly of the engine, a tiller carried by said bracket and extending forwardly of the motor unit, said tiller being rotatably adjustable on the axis of said transverse shaft and having a separately movable grip-handle at the forward end thereof, means connecting said transverse shaft and said grip-handle and said transverse and vertical shafts whereby movement of said handle effects a corresponding rotation of said shafts and adjustment of said magneto stator plate, a vertical control rod connected at its lower end to said transmission means and rotatable to different positions, an abutment member connected to said rod at the upper end thereof adjacent to said transverse shaft and shiftable with rotation of said rod in a direction lengthwise respecting said transverse shaft, a second abutment member secured on said shaft and disposed to be engaged by said first abutment member to restrict movement of the latter within preselected limits and given limits of adjustment of said magneto stator plate and the speed of the engine, and bearing means securing said transverse shaft axially respecting said bracket.

2. In an outboard motor unit pivotally supported for steering movement on a vertical axis, an engine, a magneto at the upper end of the engine and having a stator plate rotatably adjustable to control the speed of the engine, a vertical shaft at one side of the engine and connected at the upper end to said plate to adjust the latter, a lower propeller unit including transmission means selectively operable to effect a driving connection with said engine for propulsion in forward and reverse directions, a bracket carried by the motor unit and a transverse shaft supported by said bracket forwardly of the engine, a tubular tiller carried by said bracket and extending forwardly of the motor unit, said tiller being rotatably adjustable on the axis of said transverse shaft and having a separately movable grip-handle at the forward end thereof, means connecting said transverse shaft and said grip-handle and said transverse and vertical shafts whereby movement of said handle effects a corresponding rotation of said shafts and adjustment of said magneto stator plate, a vertical control rod connected at its lower end to said transmission means and rotatable to different positions, a pin connected to said rod at the upper end thereof and offset therefrom so as to be disposed and movable adjacent to said transverse shaft in a direction lengthwise thereof, a collar secured on said shaft and disposed to be engaged by said pin to restrict movement of the latter and operation of said transmission means within preselected limits of adjustment of said magneto stator plate and the speed of the engine, bearing means securing said transverse shaft axially respecting said bracket, and abutment means provided by recesses formed in said collar to engage said pin in certain positions thereof and limit the rotation of said shafts and the speed adjustment of said engine during the corresponding operation of the motor.

3. In an outboard motor unit, an engine having an adjustment means to control the speed and operation of the motor, a propeller, transmission unit carrying said propeller and including a transmission element selectively shiftable

5 to effect a driving connection with said engine and the selective rotation of said propeller in forward and reverse directions, a manually operable lever for effecting control of said transmission element including a movable rod having given positions corresponding to the shifted positions of said transmission element, abutment means comprising a pin movable transversely of the motor unit and respectively with movement of said rod, means including a handle and a shaft adjacent to said pin and rotatable whereby movement of said handle effects a corresponding rotation of said shaft and adjustment of said control means, the axis of said shaft extending in the direction of movement of said pin, and a collar mounted on said shaft for engagement with said pin and having abutments facing said pin axially of said shaft and disposed to be engaged by said pin to restrict movement of said rod and shifting of said element at predetermined speeds above that of a corresponding position of rotation of said shaft.

4. In an outboard motor unit, an engine having an adjustment means to control the speed and operation of the motor, a propeller, transmission unit carrying said propeller and including a transmission element selectively shiftable to effect a driving connection with said engine and the selective rotation of said propeller in forward and reverse directions, a manually operable lever for effecting control of said transmission element including a movable rod having given positions corresponding to the shifted positions of said transmission element, abutment means comprising a pin movable transversely of the motor unit and respectively with movement of said rod, means including a handle and a shaft adjacent to said pin and rotatable whereby movement of said handle effects a corresponding rotation of said shaft and adjustment of said control means, the axis of said shaft extending in the direction of movement of said pin, and a collar mounted on said shaft for engagement with said pin and having abutments facing said pin axially of said shaft and disposed to be engaged by said pin to restrict movement of said rod and shifting of said element at predetermined speeds above that of a corresponding position of rotation of said shaft, said collar being adjustable axially on said shaft for adjustment relative to the positions of said pin and corresponding to the shifted positions of said element.

5. In an outboard motor unit, an engine having an adjustment means to control the speed and operation of the motor, a propeller, transmission unit carrying said propeller and including a transmission element selectively shiftable to effect a driving connection with said engine and the selective rotation of said propeller in forward and reverse directions, a manually operable lever for effecting control of said transmission element including a movable rod having given positions corresponding to the shifted positions of said transmission element, abutment means comprising a pin movable transversely of the motor unit and respectively with movement of said rod, means including a handle and a shaft adjacent to said pin and rotatable whereby movement of said handle effects a corresponding rotation of said shaft and adjustment of said control means, the axis of said shaft extending in the direction of movement of said pin, and a collar mounted on said shaft for engagement with said pin and having abutments facing said pin axially of said shaft and dis-

posed to be engaged by said pin to restrict movement of said rod and shifting of said element at predetermined speeds above that of a corresponding position of rotation of said shaft, said collar being adjustable axially on said shaft for adjustment relative to the positions of said pin and corresponding to the shifted positions of said element and adjustable rotationally on said shaft for adjustment relative to said pin and a corresponding adjustment of said limits of speed control.

6. In an outboard motor unit, an engine having an adjustment means to control the speed and operation of the motor, a propeller, a lower unit carrying said propeller and including a transmission element selectively shiftable to effect a driving connection with said engine and the selective rotation of said propeller in forward and reverse directions, a bracket pivotally supporting the motor unit for steering movement on a vertical axis, a manually operable lever for effecting control of said transmission means including a rod rotatable on said axis and having given positions corresponding to the forward and reverse control of said transmission means, a tiller connected to the motor unit for effecting steering movement of the unit on said vertical axis and being adjustable respecting the motor unit on a transverse axis passing adjacent to said rod, said tiller having a handle separately movable at the end thereof, means connecting said handle and said control means and

including a shaft rotatable on said transverse axis whereby movement of said handle effects a corresponding rotation of said shaft and adjustment of said control means, a pin carried by said rod at the upper end thereof and offset from said vertical axis, and a collar fixed on said shaft for engagement with said pin and adjustable axially and rotationally thereof and with respect to said pin, said collar having abutments facing axially of said shaft and disposed to be engaged by said pin to restrict movement of said rod and shifting of said element at predetermined speeds above that of a corresponding position of rotation of said shaft and the adjustment of said speed control means to within different limits corresponding to the position of said pin, the said adjustment of said collar on said shaft providing the corresponding relative adjustments of said abutments and said pin.

ELMER C. KIEKHAEFER.
